CLAIM

The ornamental design for a push-button enlarger for attaching over telephone multifrequency tone push buttons, as shown and described.

DESCRIPTION

FIG. 1 is a front view of the push-button enlarger for attaching over telephone multifrequency tone push buttons;

FIG. 2 is a side view of the enlarger of FIG. 1, the opposite side view being identical to the one illustrated in FIG. 2;

FIG. 3 is a top plan view of the enlarger of FIG. 1; and FIG. 4 is a bottom plan view of the enlarger of FIG. 1.

*Fig. 1.**Fig. 2.**Fig. 3.**Fig. 4.*
